UNITED STATES PATENT OFFICE.

CHARLES F. SCHULTIS, OF CLEVELAND, OHIO, ASSIGNOR, BY MESNE ASSIGNMENTS, TO THE STANDARD PARTS COMPANY, OF CLEVELAND, OHIO, A CORPORATION OF OHIO.

ELEVATING-TRUCK.

1,303,601.

Specification of Letters Patent.

Patented May 13, 1919.

Application filed November 3, 1916. Serial No. 129,258.

To all whom it may concern:

Be it known that I, CHARLES F. SCHULTIS, a citizen of the United States, residing at Cleveland, in the county of Cuyahoga and State of Ohio, have invented a certain new and useful Improvement in Elevating-Trucks, of which the following is a full, clear, and exact description, reference being had to the accompanying drawings.

10 This invention relates to trucks, and more particularly to what are known to the trade as "shop trucks" which are employed in factories for the transportation of articles, the trucks being propelled in any suitable manner. It is the general object of this invention to provide a truck of the character described which may be placed beneath a platform containing articles to be transported and having a table or load-carrying part which may be elevated to enable it to lift the platform with its load and which, when the platform and load have been transported to the desired unloading station, may be conveniently lowered until the weight of the platform is taken from the truck, whereupon the truck may be transported to another similar platform and the operation be repeated. Still further and more generally stated the invention may be defined as consisting of the combinations of elements embodied in the claims hereto annexed and illustrated in the drawings forming part hereof wherein Figure 1 represents a perspective view of the truck and load-carrying platform; Fig. 2 a longitudinal central section taken through the truck; Fig. 3 a horizontal sectional view corresponding to the line 3—3 of Fig. 2; Fig. 4 a transverse sectional view corresponding to the line 4—4 of Fig. 3; and Fig. 5 a detail corresponding to the line 5—5 of Fig. 4, certain parts being shown in elevation.

45 Describing by reference characters the various parts illustrated herein, 1 denotes generally the bed or frame of the truck, said bed or frame comprising a floor 2 having vertical sides 3 and ends 4, 4^a. The bed or frame is preferably formed of a casting and is provided with a central longitudinal rib 5 forming a brace between a rear bearing sleeve 6 and a front bearing sleeve 7. On its upper surface, the floor 2 is provided with a pair of ball races 8 and 9 surrounding the sleeves or hubs 6 and 7, respectively, and 55 preferably cast with the floor.

10 and 11 denote, respectively, a rear and a front worm wheel, each having a rigid ball race 10^a and 11^a respectively, preferably cast therewith, there being balls 12, 12^a interposed between said races. Each worm gear 60 has rigid therewith a circular track, coaxial with a central sleeve or hub 13, 14, and each track has two inclines 15 and 16 respectively, providing a pair of inclines for each worm gear, the "high" point 15^a, 16^a of each incline being 180° distant from the "high" point of the other incline and each track having two "low" spots 15^b, 16^b, respectively, the low spots of each track being 180° apart. Each track has thus two inclines which are 70 adapted to coöperate with a pair of rollers, 180° apart, carried by the platform.

75 The hub of each worm gear is sleeved upon a post, 17, 18, carried respectively by the hubs 6 and 7. The table comprises a floor 19 with depending sides 20 and ends 21 forming a skirt extending about the upwardly projecting sides and ends of the bed or frame 1. The table, with its sides and ends, is preferably formed by casting, the 80 sides and ends of the table being provided with machined bearing surfaces 22 coöperating with corresponding machined surfaces 23 on the walls of the bed frame, whereby the table will be guided and centered as it is 85 reciprocated. 24 denotes triangular brackets which depend from the floor 19 and which are formed with bearings for the shafts 25 of rollers 26, there being a pair of such brackets for each roller. Four such rollers 90 are provided, the rollers being arranged in pairs at the front and at the rear of the platform, the rollers of each pair being 180° apart and being so arranged as to ride upon the tracks 15 and 16 respectively.

95 The rear axle 27 may be supported in any convenient manner by the bed 1, said axle having wheels 28 on the outer ends thereof. From the front wall 4^a there extends a yoke, preferably cast therewith, said yoke comprising a pair of upwardly inclined converging arms 29 provided at their junction with a vertical bearing 30 for a shaft 31 which projects upwardly from a bracket 32 supporting the shaft or axle 33 of a caster wheel 34. If 100 desired, an antifriction bearing 35 may be interposed between the bottom of the hub or sleeve 30 and the top of the bracket 32.

105 The front wall 21 of the table is recessed, as indicated at 21, for the reception of the 110

yoke arms 29. The truck illustrated herein is a small or hand propelled truck and is provided with the tongue 36 which is pivotally connected to the ends of the shaft 33 by means of a yoke 37.

For the purpose of rotating the worm gears 10 and 11 and the tracks carried thereby, the following construction is provided:

- 10 38 denotes a post which may be cast with a bracket 39 in front and at one side of the bed frame. 40 denotes an inclined brace for said post, the brace being preferably cast with the post and riveted or otherwise suitably secured to one of the yoke arms 29, as indicated at 41. 42 denotes a sprocket which is journaled on the upper end of an extension 38^a of the post 38 and provided with an operating crank arm 43. 44 denotes a sprocket which is rigid with a worm shaft 45 extending lengthwise of the skirt 20^a and supported by journals 20^b projecting laterally therefrom. Power may be transmitted from the sprocket 42 to the sprocket 25 44 as by means of a noiseless chain 46. The shaft 45 is provided with a pair of worms 46 and 47 meshing respectively with the worm gears 10 and 11. The extension 38^a is socketed into the top of the post 38 and 30 may be adjusted longitudinally of said post to compensate for the wear of the chain 46, a set screw 38^b being employed to retain the extension in its various adjusted positions, the extension having a flattened tapered surface 38^c for engagement by the set screw—see Fig. 5.

With the parts constructed and arranged as described, the operation will be easily understood. The truck, with the table in 40 its lowered position, is placed beneath the load-supporting platform 48, the rollers 26 at this time being on the lowest portion of their respective tracks. The crank 43 is operated thereby driving the worm shaft 45 45 and rotating the worm gears 10 and 11, which will cause the rollers 26 to ride up the inclines 15 and 16 until the platform 48 with its load has been lifted, whereupon the truck may be transported to the desired 50 unloading station and, by operating the crank 43 farther in the same direction, or in the reverse direction, the table 19 will be lowered and the platform 20 will be positioned on the floor, whereupon the truck 55 may be transported to another place and the operation repeated.

The construction of truck disclosed herein is extremely simple and economical of production, since practically all of the parts 60 may be made as castings, but is extremely convenient and efficient in operation. While I have shown my invention as embodied in a small hand-propelled truck, it will be evident that it is capable of being embodied in 65 various forms and constructions of vehicles;

and I do not propose to be limited to the details of construction illustrated herein except as such limitations may be positively included in the claims hereto annexed or the inclusion of such details may be rendered necessary by the state of the prior art.

I claim—

1. In a vehicle of the character described, the combination of a frame, a load carrying table having a depending skirt, said skirt being spaced from said frame, interengaging guides carried by said skirt and the frame, and means for raising and lowering the table with reference to the frame.

2. In a vehicle of the character described, the combination of a frame having upwardly extending sides and ends, a load-carrying table having a depending skirt arranged externally of the said sides and ends, said skirt being spaced from said frame, interengaging guides carried by the skirt and said sides and ends, and means for raising and lowering the table with reference to the frame.

3. In a vehicle of the character described, the combination of a frame, a pair of longitudinally spaced horizontally disposed rotary inclined tracks carried by said frame, a load carrying table having means adapted to engage said tracks, and means for rotating said tracks thereby to raise and lower said table with reference to the frame.

4. In an apparatus of the character described, the combination of a frame, a pair of horizontally disposed gears rotatably mounted on said frame and spaced longitudinally thereof, an inclined track carried by each of said gears, a table having depending rollers adapted to engage the upper surface of said tracks, and means for driving said gears, one in the counter-clockwise direction and the other in a clock-wise direction thereby to raise or lower said table.

5. In a vehicle of the character described, the combination of a frame, a pair of gears journaled on said frame and rotatable each about a vertical axis, a continuous inclined track carried by each of said gears, a table having depending rollers adapted to engage said tracks, and means for driving said gears thereby to raise and lower said table.

6. In a vehicle of the character described, the combination of a frame having a pair of gears supported thereby and rotatable each about a vertical axis, a track carried by each of said gears, each track having two circumferentially spaced inclines, a table having a roller for each inclined portion of said tracks, and means for driving the gears simultaneously in opposite directions thereby to raise and lower said table.

7. In a vehicle of the character described, the combination of a frame having longitudinally spaced supports for vertically extending shafts, means for bracing said sup-

ports, and a raceway surrounding each of said supports, a vertical shaft in each of said supports, a gear on each of said shafts each having a raceway corresponding with the 5 raceway on the frame, anti-friction devices interposed between said raceways, an inclined track carried by each of said gears, a table, means carried by the table adapted to engage each of said tracks, and means for 10 driving the said gears thereby to raise and lower the table.

8. In a vehicle of the character described, the combination of a frame, a pair of worm 15 gears supported by said frame and rotatable each about a vertical axis and each having a rotary track provided with an incline, said track being coaxial with said gears, a shaft carried by said bed or frame and having a worm meshing with each of said gears, 20 and a table having means adapted to engage the tracks whereby the table may be raised and lowered by the rotation of the said shaft.

9. In a vehicle of the character described, the combination of a frame having a pair of 25 longitudinally spaced hubs and a rib connecting said hubs or sleeves and provided with a raceway surrounding each hub, a shaft in each hub, a gear on each shaft and each having a raceway coöperating with one of 30 the first-mentioned raceways, there being anti-friction devices interposed between said raceways, a circular track on each of said gears, each track having a pair of opposed inclines, a table, rollers depending from 35 said table and adapted to engage and be operated by the inclined portions of said tracks, a shaft, and gears on said shafts co-operating with the first mentioned gears whereby the rotation of the shaft will operate 40 said gears to raise and lower said table.

10. In a vehicle of the character described, the combination of a frame, a pair of longitudinally spaced gears carried by the bed or frame and each rotatable about a vertical axis and each having an inclined track, a 45 table having portions adapted to engage the tracks, a shaft having gears thereon adapted to mesh with the first-mentioned gears, a sprocket on said shaft, a post projecting upwardly from the said frame, a sprocket 50 on said post, a chain coöperating with said sprockets, and means connected with the sprocket on the post for rotating the same.

11. In a vehicle of the character described, the combination of a frame having cast 55 therewith a pair of circular raceways, a pair of gears each having a circular raceway co-operating with one of the first mentioned raceways and each having a circular track provided with a pair of oppositely disposed 60 inclines, a table having a depending skirt formed therewith, the said skirt and the bed or frame having interengaging guides, rollers depending from the table and adapted to engage the inclines on the tracks, a shaft 65 on said frame having a driving connection with each of said gears, and means for driving said shaft.

12. In a vehicle of the character described, the combination of a frame, a load carrying table, a continuous rotary track supported by the frame, said track being rotatable about a vertical axis, and connections between said table and said track whereby the table may be raised and lowered by rotating said track in the same direction. 70 75

In testimony whereof, I hereunto affix my signature.

CHARLES F. SCHULTIS.
